UNITED STATES PATENT OFFICE.

JOSEPH P. M. EARTY, OF POLK, OHIO.

PUMP.

SPECIFICATION forming part of Letters Patent No. 402,149, dated April 30, 1889.

Application filed March 3, 1888. Serial No. 266,090. (No model.)

To all whom it may concern:

Be it known that I, JOSEPH P. M. EARTY, a citizen of the United States, residing at Polk, in the county of Ashland and State of Ohio, have invented a new and useful Improvement in Pumps, of which the following is a specification.

My invention relates to an improvement in double-acting force and lift pumps; and it consists in the peculiar construction and combination of devices that will be more fully set forth hereinafter, and particularly pointed out in the claims.

In the accompanying drawings, Figure 1 is a longitudinal vertical sectional view of a pump embodying my improvements. Fig. 2 is a horizontal transverse sectional view of the same, taken on the line $x-x$ of Fig. 1. Fig. 3 is a similar view taken on the line $y-y$ of Fig. 1. Fig. 4 is an enlarged detail sectional view of the plunger.

A represents the outer cylinder, which is of suitable length and diameter, and is provided with external screw-threads at its upper and lower ends.

B represents a cap, which is substantially semi-spherical in shape, and is provided at its lower edge with a depending internally-threaded flange, C, which is adapted to be screwed to the upper end of cylinder A. An annular shoulder, D, is formed on the inner side of the cap, at the upper side of said flange.

E represents a circular ring or plate having a large central opening, F, and provided with a series of small radial openings, G, between said opening F and its perimeter. On the upper side of the said ring E is placed a valve-ring, H, of similar size and shape, which valve-ring is made of leather or other suitable material. The said valve-ring and plate E are secured on the upper edge of cylinder A, between the same and the shoulder D of cap B, the said valve-ring being on the upper side of the ring or plate E and normally closing the openings G thereof.

I represents an inner cylinder, the diameter of which is less than the diameter of the cylinder A. The said inner cylinder is arranged in the center of cylinder A, and has its upper end screwed into the central opening, F, of the ring E. The lower end of the cylinder I is also provided with screw-threads.

K represents a valve-ring, which is similar to the valve-ring H and is arranged against the lower edge of the inner cylinder, I.

55

L represents a circular plate or head which forms the lower end of the inner cylinder, I, and is provided near its perimeter with a circular series of openings, M, which are arranged under the valve-ring K, and N represents a ring or collar which is screwed to the lower end of the inner cylinder, I, and is provided at its lower side with an inwardly-projecting annular flange, O, which engages the lower side of the head or plate L and secures the same and the valve-ring K firmly in position on the lower end of the inner cylinder, I.

P represents a lower cap, which is similar in size and shape to the upper cap, B, and is screwed to the lower end of the cylinder A. 70 From this cap P depends a suction-pipe, R, which is provided with a ball-valve, S, in a valve-chamber, T, and has also a ball-valve, U, at its upper end in the lower end of the cap or head P.

The upper cap, B, has a central opening in which is screwed the lower end of a pipe, V. The upper end of the said pipe V is provided with a discharge-spout, W, and has a link, X, to which link is fulcrumed a lever, 80 Y. To the inner end of the said lever is pivoted the upper end of rod Z, and the lower end of the said rod connects with the upper end of a tubular rod or pipe, A', which extends downward into the inner cylinder and 85 is provided near its upper end with an opening, B', which communicates with a pipe, V.

C' represents a packing, which is arranged in the pipe V near the lower end thereof, and through which the tubular rod A' extends. 90 To the lower end of said tubular rod is secured a plunger, D', the construction of which is as follows:

a represents the upper section, which is substantially semi-spherical in shape, and is provided on its lower side with an annular channel, b, thereby forming a depending flange, c. The said flange has an opening, d, that communicates with the channel. From the lower side of the section a, and formed integrally therewith, depends a stud, e. In the upper portion of the stud e is a cavity, f, which is in the form of an inverted cone. The upper end of this cavity communicates with the

tubular rod A'; and the lower end thereof has a semi-spherical recess, h. i represents a valve, which is arranged in the cavity f, and has a ball, k, at its lower end, which is socketed in the recess h. On opposite sides of the cavity f, and communicating with the same, are openings or channels g and l. The said opening or channel g is on a lower plane than the opening l, and to the latter communicates with the channel b. The valve h is adapted to be moved against the opening g and l, so as to close one and open the other at the same instant. m represents a lower section, which is semi-spherical in shape, and has its lower end truncated or flattened, as shown. On the upper side of the lower section is formed an annular flange or collar, n, which is adapted to enter the channel b of section a. A vertical central opening is made through the section m of sufficient diameter to receive a stud, e, and communicating with the said opening is an annular channel, o, having an opening, p, on one side. The said channel o communicates with the opening g of stud e.

Arranged between the opposing sides of the sections a and m are a pair of leather packing or cylinder rings, s, which have their outer edges turned upward and downward, as shown, and thereby adapted to fit snugly against the inner side of cylinder I. r represents a nut, which is screwed onto the lower threaded end of stud e, and serves to force the lower section, m, upward on said stud and clamp the packing-rings firmly between said section m and upper section, a.

By operating the pump-lever the plunger may be caused to reciprocate vertically in the cylinder I.

40 The operation of my invention is as follows: On the upstroke of the plunger the valve h closes against the opening g, and thereby cuts off communication between the hollow rod A' and the lower portion of the cylinder I. The pressure of the air in the upper portion of said cylinder I closes the valve h, and a partial vacuum is formed in the lower portion of cylinders I and A, which causes the valves S U K to open, and thereby water is sucked into the lower end of said cylinders I and A. A portion of this water passes up through the annular space between said cylinder and finds its way through the valve-ring E into the upper portion of cylinder I, and is compressed by the upward movement of the plunger and forced upward thereby through the opening d l and cavity into the hollow rod A', and from the latter into the lower portion of the delivery-pipe V. The valves H, K, U, and S close by their own gravity and by the pressure of the superincumbent water when the plunger reaches

the upper limit of its movement; and on the ensuing downstroke of the plunger the valve i closes against the opening l, thereby opening communication between the lower portion 65 of the inner cylinder and the tubular rod A'. A partial vacuum is formed in the upper portion of the cylinder I, which causes water from the cylinder A to be sucked into the upper portion of cylinder I through the valve plate 70 or ring E and past the valve H, and the water in the lower portion of cylinder I becomes compressed by the descent of the plunger, thereby keeping the valve K closed, and the water in the lower portion of cylinder I is 75 thus forced upward through the hollow rod A' into the delivery-pipe V.

From the foregoing description it will be understood that the plunger both sucks and forces water at each stroke, whether up or 80 down, and consequently a continuous stream of water is discharged from the spout of the discharge-pipe when the pump is in operation.

Having thus described my invention, I claim— 85

1. In a pump, the combination of the outer cylinder, the cap secured to the upper end of the same, the ring E, and the valve-ring D, clamped between the cap and the outer cylinder, the inner cylinder secured to the ring 90 E, the valve-ring K at the lower end of the inner cylinder, the plate L, the collar N, secured to the lower end of the inner cylinder and clamping the plate L and ring K against the inner cylinder, and the plunger reciprocating in said inner cylinder, as specified. 95

2. The plunger having the sections a and m, said section a having the channel b, the recess f, communicating with the said channel, said section m having the channel o, also 100 communicating with the said recess, and the valve arranged in the said recess and adapted to alternately cut off communication between the same and the channels b and o, substantially as described. 105

3. The combination of the section a, having the channel b, the depending stud e, the recess f, formed in said stud and communicating with channel b, the section m, fitted on the stud and having the channel o, communicating with recess f, the valve i, arranged in the said recess, the nut r, screwed to the lower end of the stud, and the packing-rings s, clamped between the sections a and m, substantially as described. 110 115

In testimony that I claim the foregoing as my own I have hereto affixed my signature in presence of two witnesses.

JOSEPH P. M. EARTY.

JAMES J. BERRY,
FREDRICK HARTSEL.

Correction in Letters Patent No. 402,149.

It is hereby certified that the name of the patentee in Letters Patent No. 402,149, granted April 30, 1889, for an improvement in "Pumps," was erroneously written and printed "Joseph P. M. Earty," whereas said name should have been written and printed *Joseph P. McCarty*; and that said Letters Patent should be read with this correction therein that the same may conform to the record of the case in the Patent Office.

Signed, countersigned, and sealed this 9th day of July, A. D. 1889.

[SEAL.]
